UNITED STATES PATENT OFFICE.

JAMES L. LOWE, OF DURHAM, NORTH CAROLINA, ASSIGNOR TO THE GOLDEN BELT MANUFACTURING COMPANY, OF SAME PLACE.

BAG-SEWING MACHINE.

SPECIFICATION forming part of Letters Patent No. 416,474, dated December 3, 1889.

Application filed May 15, 1889. Serial No. 310,804. (No model.)

To all whom it may concern:

Be it known that I, JAMES L. LOWE, of Durham, county of Durham, and State of North Carolina, have invented certain new and useful Improvements in Bag-Machines, of which the following is a specification, reference being had to the accompanying drawings.

My invention relates to improvements in machines for making cloth into bags, and especially for making tobacco-bags, though also adapted to make bags of larger size.

In order that the operation of my machine may be more readily comprehended in detail, I will give a general description of its mode of operation.

Cloth of desired width is mounted upon a spool and passed beneath a roller, which stretches it between the spool and the roller, between these parts are located hemmers and sewing-machines, which fold each edge of the cloth and sew it down. The cloth is next folded in the middle and then pressed and creased between vertical rollers. It is then turned from the vertical to the horizontal position and is passed beneath another roller, which operates to draw it through the machine. It is then passed by means of an intermittently-moving roller to a knife which is adjusted to cut off a piece of the desired width. This piece is then passed from the knife to a second set of machines, which sew it up the sides and complete the bag.

An objection has hitherto existed against bag-machines, because the sewing of the sides of the bag together, which is preferably done by a single-thread machines, is commenced at the bottom and ends at the top. The consequence is that, stitching of this description being easy to ravel backward, the mouth of the bag, upon which is the greatest strain in use, is weakened, so that, in fact, it has been found necessary almost to entirely discard single-thread machines in practice. In my invention I reverse the operation and sew from the top to the bottom. In my machine all the sewing-machines are on one plane and the needle-bars work in vertical planes. By this means the machine itself is simplified and the operation is direct.

In the accompanying drawings, Figure 1 is

a plan view of the upper side of my machine, showing it filled with cloth, as in use. Fig. 2 is a plan view of the bottom of my machine. Fig. 3 is an elevation of one side of my machine, and Fig. 4 an elevation of the opposite side. Fig. 5 is a section along the line $\alpha\alpha$ of Fig. 1, showing the cutting-machine and the feed to the second set of machines. Figs. 6 and 7 are detail views of parts of my machine detached.

In the above-described illustration the bed of the machine and the parts connected therewith are shown without means of support, as the bed may be supported by legs or by usual means, the showing of which would have tended to obscure the working parts. Thread in practice is supplied to the sewing-machines from large spools fixed upon the floor beneath the machine; but these are not indicated in the drawings.

Referring to the letters upon the drawings, A indicates the bed-plate of my machine.

B indicates a main driving-shaft, and C a split pulley secured thereto.

D D indicate cog-gears adjustably secured to the shaft B and gearing with the pinions E E of the sewing-machine F F. The sewing-machines are sunk below the surface of the bed-plate, so that their feed-plates are in the same plane with the bed-plate of the machine proper. They may be of any desired pattern or construction; but it is preferable to use single-thread machines, the right and left machine being adapted in a well-known manner to feed in the same direction. The machines F F are in practice generally made adjustable upon the bed-plate A, so as to suit different widths of cloth.

G indicates a support for the spool H, and I I hemmers for folding each side of the cloth before it reaches the machine. Mounted upon the bed-plate is a knurled roller J, upon one end of whose axis is carried a worm-threaded pulley K, through which, by means of the stirrup-gear L and worm M, motion is communicated from the shaft B to the roller J. The worm M is weighted at its outer end, so that it may be readily detached from the pulley K. Any well-known means, however, of forming a detachable connection between said pulley and the shaft B may be adopted.

N indicates a revolving shaft supported upon the bed-plate A and receiving motion through the spur-gearing O from the axis of the roller J. By means of the spur-gear P motion is imparted from the shaft N to the shaft Q, and that through the spur-gear R imparts motion to the vertical roller S, which is supported by the frame T upon the bed-plate A. In contact with the roller S is a corresponding roller S', which by friction derives its motion from the roller S.

U indicates a folder, which consists of a standard supported upon the bed-plate and carrying at its upper end a thin-edged roller, which serves to fold the cloth in the middle and to present it folded to the rollers S S'.

V indicates a guide. It consists of a sheet of metal folded so as to leave a space between the parts and twisted so that one end is at right angles to the opposite end of it. The folded cloth from the rollers S S' is passed into the guide and turned by it from a vertical to a horizontal position, and there presented to the roller W, which is journaled upon the bed-plate A, and by means of the spur-gear X derives a constant motion from the shaft N. The velocities of the rollers J, S, S', and W are equal, but are less than that of the shaft B, to which they are geared, being regulated to the feed of the sewing-machine.

Y indicates a roller journaled upon the bed-plate and carrying loose upon its axis A' the worm gear wheel B', which, by means of the pawl-and-ratchet mechanism C', (shown in Fig. 6,) is adapted to communicate motion in one direction to the roller Y.

D' indicates a vertical worm, which gears with the wheel B', and is pivotally carried upon the knife-head E' by the arm F'. By 40 this means it will appear that when the knife-head descends the gear-wheel B' will turn loosely upon its axis; but when it moves in the opposite direction it will cause the roller Y to revolve. While the roller Y is stationary there is an accumulation of cloth between it and the roller W, which may be taken up in any convenient way—for instance, by a rod a passing underneath the cloth and held against it by the cord b, attached to it at one 45 end and weighted at the other, as shown in the drawings. The wheel B' in practice is so geared with its worm D' as to impart a high velocity to the roller Y and to take up all the accumulated slack of the cloth while the 50 knife-head is ascending.

G' indicates guides or bearings secured to the bed-plate A and carrying the vertically-movable rods H', the upper end of each of which is secured to the knife-head E', carrying the 60 knife I'. An intermittent motion is imparted to the knife-head E', so that when the cloth has been fed out by the roller Y to any predetermined length the knife descends and cuts it off. Instantly succeeding this operation the claw K' seizes the cloth and pushes it in the direction of the sewing-machines L', which operate in the same manner as those

described above. The claw is operated by the rod M', which rides upon the rollers N', projecting from a support secured to the 70 knife-head E', in practice preferably made adjustable. The rod M' is adjustably secured by means of the slots c and thumb-screw d to the rod O', pivotally supported at P' to the bed-plate A.

Q' indicates a revolving shaft, which is connected with the shaft B by the spur-gear R', and by means of cog-gear T' and the pinions U' drives the sewing-machines L'.

V' indicates a cross-bar adjustably secured 80 to the lower ends of the rods H', and adapted to receive and communicate motion to the knife-head E' from the cam W', mounted upon the shaft X'. The shaft X' derives its motion from the shaft Q' by means of the 85 cog-gear connection Y'.

Z' indicates another cam borne upon the shaft A' and geared to the shaft Q'.

B² indicates a frame adapted to receive a reciprocating motion from the cam Z'. It 90 slides in the hanger C², and is secured at one end by the rod D² to the rod O' and at the other by a spiral spring E² to a perpendicular projection extending from the bed-plate A.

F² indicates spiral springs secured at one 95 end to the bottom of the bed-plate A and at the other to the cross-bar V'.

The above-mentioned springs serve to hold their respective bearings against each of said cams. The springs F² assist the cam W' to 100 operate the knife by tending to keep it elevated. The spring E² assists the cam Z' to operate the claw K', and gives to the latter an abrupt retraction after it has completed each push.

The above-named cams are so geared to the shaft Q' and so timed with reference to each other that when the cam W' is at its lowest point the cam Z' is at its farthest throw. In other words, when the knife-head 110 E' is in its highest position the claw K' has been pushed forward to its limit. It will be observed that the cam W' is a regular round cam of usual construction, while Z' is irregular, and adapted to impart an abrupt quick 115 movement to the frame B², and through it to the claw K'.

G² indicates a brake pivoted to the bed-plate, and pressed by the spring H² against the spool I to retard its motion and prevent 120 its paying off the cloth too fast to the sewing-machines.

It is preferable in practice to make the feed-rollers adjustable to suit different thicknesses of cloth.

In Fig. 7, e indicates a roller-journal, which is provided with pins f f, corresponding to the dowels g in the bed-plate of the machine. Beneath the bed-plate is fastened a support h for the nut i, which is screw-threaded to receive the screw k, secured at its upper end to the journal e. A turn or two upon the nut i is sufficient to afford the slight adjustment necessary for the feed-roller.

What I claim is—

1. A bag-machine consisting of the following elements in combination, namely: a pair of folders to turn the edges of the cloth down upon the body, a pair of sewing-machines to complete the hems, a horizontal feed-roller to assist the feed of the said machines, two vertical presser-rollers, a folder between the horizontal and the vertical rollers to double the cloth, a cutter to sever a sufficient portion of the doubled cloth to make a bag, and a second pair of machines to sew up the sides of the bag at right angles to the hem, substantially as described.
- 15 2. In a bag-machine, the combination, with two sewing-machines and hemmers, of a folder and vertical presser-rollers, a horizontal feed-roller, a guide for turning the folded cloth from the vertical to a horizontal position, a cutter to sever the width of a bag from the folded cloth, and machines to sew up the sides of the bag, substantially as described.
- 25 3. In a bag-machine, the combination, with two sewing-machines and hemmers, of a cutter, a folder between the said machines and the cutter, and machines for sewing up the sides of the bag, substantially as described.
- 30 4. In a machine by which a roll of cloth is hemmed, folded, cut into sizes, and stitched together into bags, the combination of a set of vertical rollers to press together the folded

cloth, a horizontal feed-roller, and a guide by which the cloth is passed from the vertical rollers to the horizontal one, substantially as described.

5. In a bag-machine, the combination, with a pair of sewing-machines and hemmers, of a cutter, folding mechanism between the said machines and the cutter, a second pair of sewing-machines to stitch up the sides of the bag, and a horizontal feed mechanism between the cutter and the second set of machines, whereby the folded material is stitched from the hem toward the crease to form a bag, substantially as described.

40 6. In a bag-machine provided with an alternately-moving knife and feed-roller, the combination of a worm geared wheel turning loose upon the axis of said roller, a pawl-and-ratchet connection between said axis and said wheel, and a worm carried upon the head of said knife and adapted to gear with said wheel, and thereby impart an intermittent motion to said roller, substantially as described.

45 In testimony of all of which I have hereunto subscribed my name.

JAMES L. LOWE.
